UNITED STATES PATENT OFFICE.

GAYLE L. SQUIRE, OF HASTINGS, FLORIDA.

BARREL, WINE, AND LARD PRESS.

1,344,156.

Specification of Letters Patent. Patented June 22, 1920.

Application filed January 26, 1920. Serial No. 354,112.

To all whom it may concern:

Be it known that I, GAYLE L. SQUIRE, a citizen of the United States, residing at Hastings, in the county of St. John and 5 State of Florida, have invented a new and useful Barrel, Wine, and Lard Press, of which the following is a specification.

The device forming the subject matter of this application is a press, adapted to be 10 employed for inserting the heads into barrels.

One object of the invention is to provide 15 novel means for exerting pressure on the head while the same is being inserted into the barrel.

Another object of the invention is to provide 20 novel means whereby the head of the barrel may be mounted on the pressing mechanism, before the pressing mechanism is operated to insert the head into the barrel.

It is within the province of the disclosure 25 to improve generally and to enhance the utility of devices of that type to which the invention appertains.

With the above and other objects in view, 30 which will appear as the description proceeds, the invention resides in the combination and arrangement of parts and in the details of construction hereinafter described 35 and claimed, it being understood that, within the scope of what is claimed, changes in the precise embodiment of the invention shown can be made without departing from the spirit of the invention.

In the accompanying drawings:—

Figure 1 shows in side elevation, a device 40 constructed in accordance with the invention, parts being broken away; Fig. 2 is a front elevation wherein the front plate of the casing has been removed, in order that certain operating mechanisms may appear.

In carrying out the invention there is provided 45 a frame, comprising a base 1 having openings 2 adapted to receive securing elements 3, whereby the base 1 may be attached in vertical position to a post 4 or the like. Adjacent to its lower end, the base 1 is supplied with a vertical stop wing 5. The stop wing 5 has an opening 6 located relatively 50 near to the base 1. A lower bracket 7 is formed integrally with the stop wing 5 and with the base 1 and is horizontally disposed. Adjacent to its upper end, the base 1 is supplied with an outwardly projecting upper bracket 8 located above the lower bracket 7. The base 1 is provided, along the edge op-

posite to the edge from which the stop wing 5 projects, with a lower stop rib 11 and with an upper stop rib 12.

A guide rod 9 is mounted in the brackets 60 7 and 8, in spaced relation to the base 1, and is held against longitudinal movement in brackets 7 and 8. A frame 14 is mounted at its inner end on the guide rod 9 for vertical sliding movement, and for horizontal swinging movement, the frame 14 comprising spaced arms 15, the rear ends of which are mounted on the guide rod 9, to afford a vertical sliding adjustment of the frame and to provide for a lateral swinging 65 movement of the frame, as above described. The forward ends of the arms 15 are connected to a casing 16, a reinforcing flange 17 being formed integrally with the arms 15 and with the rear wall of the casing 16. 70 The casing is closed at its forward side by a face plate 18 held in place by securing elements 19.

A horizontal shaft 20 is journaled for rotation in the side portions of the casing 16 80 and extends across the interior of the casing. The shaft 20 is supplied, externally of the casing 16, with cranks 21 or other suitable means whereby rotation may be imparted to the shaft. Worms 22 are secured as indicated at 23 to the shaft 20 and are located in the casing 16. The worms 22 mesh into worm wheels 24, formed integrally with, or otherwise connected to, pinions 25, the worm 85 wheels and the pinions being located within the casing 16. The pinions 25 are supplied with hubs 26 journaled in the face plate 18, the worm wheels 24 being provided with hubs 27 mounted to rotate in the rear wall 90 of the casing 16, the pinions and the worm 95 wheels being housed in the casing 16, to the rear of the face plate 18.

A plunger 28 is mounted for vertical reciprocation in the casing 16, to the rear of the face plate 18 and in front of the worm 100 wheels 24. The plunger 28 preferably is in the form of a bar, provided on its opposite edges with racks 29 into which the pinions 25 mesh. A foot 30 is secured to the lower end of the plunger 28 and is held securely 105 thereon by brace blocks 31. The foot 30 is provided with means for engaging and holding a barrel head, said means preferably being in the form of depending prongs 32. A helical compression spring 33 surrounds 110 a portion of the guide rod 9, the upper end of the helical spring abutting against the

lower one of the arms 15 of the frame 14, the lower end of the spring abutting against the lower bracket 7 on the base 1. A latch 34 is pivoted at 35 to the upper bracket 8 for vertical swinging movement, and is provided with a side handle 36. The numeral 37 marks a retractile spring, the rear end of which is secured, as indicated at 38 to one edge of the base 1. A securing device 39 attaches the forward end of the spring 37 to the latch 34.

The invention comprises a support 40, adapted to hold the head of a barrel, the support embodying a lever 41 extended 15 through the opening 6 in the stop wing 5 and mounted to swing vertically in the stop rib 11, the lever being fulcrumed intermediate its ends as shown at 42, upon the base 1. A receptacle 43, adapted to hold a barrel 20 head, is carried by one end of the lever 41.

In practical operation, one or more barrel heads are placed in the receptacle 43 of the lever 41. The frame 14 then is swung side-wise, into the dotted line position of Fig. 2 25 until the foot 30 on the lower end of the plunger 28 is directly above the receptacle 43. The right hand end (Fig. 2) of the lever 41 is then struck a smart blow, the lever tilting on its fulcrum 42 and the receptacle 43 being carried upwardly. By this 30 operation, the barrel head in the receptacle 43 is engaged with the prongs 32 on the foot 30 of the plunger 28. The frame 14 is now 35 swung around until it projects forwardly with respect to the base 1, as shown in Fig. 1. This operation disposes the foot 30 of the plunger 28, and the barrel head carried thereby, directly above the barrel (not shown) which is to be headed. The frame 40 14 may now be slid downwardly on the guide rod 9, so as to bring the foot 30 and the barrel head thereon relatively close to the upper end of the barrel which is to be headed up. The latch 34 is swung downwardly 45 on its pivotal mounting 35 and engages the upper one of the arms 15 of the frame 14, to hold the frame depressed. It is to be observed that the device 39 which connects the forward end of the spring 33 with the latch 34 is so located with respect 50 to the pivotal mounting 35 of the latch that the spring will hold the latch in place when the latch is swung downwardly to engage with the upper one of the arms 15 of the frame 14 as indicated in Fig. 2. Further, when the latch 34 is swung outwardly and 55 backwardly, into engagement with the base 1, as shown in Fig. 1, the spring 33 will hold the latch in the position to which it has been moved, owing to the specific location of the securing device 39 with respect to the pivotal mounting 35 of the latch. After the 60 frame 14 has been swung into forwardly projecting position with respect to the base 65 1, and after the frame has been held down,

against the action of the spring 33, by the latch 34, the shaft 20 may be rotated through the instrumentality of one or both of the cranks 21. The oppositely threaded worms 22 coöperate with the worm wheels 70 24 and rotate the pinions 25, the pinions 25 coacting with the racks 29 of the plunger 28 to cause a depression of the plunger, the head of the barrel thus being forced into the open upper end of the barrel by the foot 30 75 whereon the head of the barrel is held by the prongs 32. After the head has been seated in the end of the barrel, the latch 34 may be swung backwardly into the position of Fig. 1, the handle 36 of course, constituting 80 means for manipulating the latch. When the latch 34 is swung backwardly out of engagement with the upper one of the arms 15 of the frame 14, the frame will rise, responsive to the action of the spring 33. When 85 the frame 14 is swung to one side on the guide rod 9 to position the foot 30 above the receptacle 43 of the lever 41, the arms 15 of the frame engage with the stop ribs 11 and 12. When the frame 14 is swung 90 into the position shown in Fig. 1 prior to the mounting of the head in the barrel, the lower arm 15 of the frame abuts against the stop wing 5, and, thus, the frame is held in 95 outstanding relation with respect to the base 1 at right angles thereto. Owing to the fact that, as clearly shown in Fig. 2, the worm wheels 24 are of larger diameter than the pinions 25, and since the rack bar 28-29, together with the worms 22, form parts of 100 the structure, it will be obvious that a great mechanical advantage is afforded when the head is pressed into the barrel, it being necessary to exert but a slight force on the shaft 20, by means of the cranks 21, in order 105 to obtain an exceedingly great pressure at the foot 30.

Having thus described the invention, what is claimed is:—

1. In a barrel heading machine a vertically movable head support; a frame; a heading member movably mounted on the frame and provided with means for holding a head when the head is raised by the head support; means carried by the frame for actuating said member to effect the heading operation; and means for mounting the frame for lateral swinging movement thereby to bring the heading member above the head support. 110

2. A device of the class described, constructed as set forth in claim 1, and further characterized by the fact that the head support is in the form of a lever; and a base whereon the frame is mounted for lateral 125 swinging movement, the lever being fulcrumed on the base. 120

3. A device of the class described, constructed as set forth in claim 1, and further characterized by the provision of spring 130

means for raising the frame; and mechanism under the control of an operator for holding the frame depressed, against the action of said spring means.

- 5 4. In a device of the class described, a base; a guide carried by the base; a frame mounted for reciprocation on the guide; a spring coöperating with the lower portion of the frame to raise the frame; a latch pivoted to the base and coöperating with the
- 10 upper portion of the frame to hold the frame

depressed, against the action of the spring; a heading plunger mounted to reciprocate in the frame; and means assembled with the frame for actuating the plunger.

15

In testimony that I claim the foregoing as my own, I have hereto affixed my signature in the presence of two witnesses.
